(57) **CLAIM**

The ornamental design for a foot covering for fitness and dance, as shown and described.

DESCRIPTION

FIG. 1 is a front, top, right side, perspective view of a foot covering for fitness and dance showing my new design for a left foot, the right foot being a mirror image thereof; FIG. 2 is a rear, bottom, left side, perspective view thereof; FIG. 3 is a top plan view thereof;

FIG. 4 is a right side elevational view thereof;

FIG. 5 is a left side elevational view thereof;

FIG. 6 is a bottom plan view thereof;

FIG. 7 is a rear elevational view thereof; and,

FIG. 8 is a front elevational view thereof.

Features illustrated with the broken lines, including the dashed-dot lines, form no part of the claimed design and are merely to illustrate an exemplary environment for the portion illustrated with solid lines.
